(57) **CLAIM**

The ornamental design for a pennant with whirligig, as shown and described.

DESCRIPTION

FIG. 1 is a perspective view of a pennant with whirligig, showing our new design;

FIG. 2 is a top plan view, thereof;

FIG. 3 is a front elevational view, thereof;

FIG. 4 is a right side view, thereof;

FIG. 5 is a left side view, thereof;

FIG. 6 is a rear elevational view, thereof; and,

FIG. 7 is a bottom plan view, thereof.

The broken lines showing environment in the drawings are for illustrative purposes only and form no part of the claimed design.
